United States Patent Office

Des. 194,568
Patented Feb. 12, 1963

194,568

DELEAVER

Dana W. Mox, Glenview, Ill., assignor to Uarco
Incorporated, Chicago, Ill., a corporation of Illinois

Filed June 19, 1961, Ser. No. 65,644

Term of patent 14 years

(Cl. D64—11)

FIG. 1

FIG. 2

FIG. 3

The back of the device is plain and unornamented.

I claim:

The ornamental design for a deleaver, as shown and described.
